[57] CLAIM

The ornamental design for a peritoneal dialysis catheter
implanter, as shown and described.

DESCRIPTION

FIG. 1 is a front elevational view of a peritoneal dialysis
catheter implanter showing our new design;

FIG. 2 is a left side elevational view thereof;

FIG. 3 is a right side elevational view thereof;

FIG. 4 is an enlarged top plan view thereof, taken along line
4—4 of FIG. 1;

FIG. 5 is bottom plan view thereof, taken along line 5—5 of
FIG. 1;

FIG. 6 is a rear elevational view thereof; and,

FIG. 7 is a perspective view thereof.
